SIPHONAGE BREAKER

George L. Smith and Ward F. Smith,
Canoga Park, Calif.

Application June 5, 1934, Serial No. 729,044

1 Claim. (Cl. 4—70)

This invention relates generally to toilets and more specifically to an attachment for use in connection therewith for preventing water within the flush tank or closet bowl from being drawn into the system by siphonic action.

Should a valve or faucet (at a lower level) be opened under conditions when a toilet flush tank is partly filled and the water pressure is reduced, or the supply shut off a siphonic action will take place through the piping resulting in drawing the flushing water from the tank into the system.

While this state only exists under conditions as above set forth, the admission of water from the flush tank into the system causes the same to become contaminated either with disease germs or slime that accumulates within such tanks.

Flush tank ball cock valves are usually provided with refill tubes which, under normal conditions, would prevent a siphonic action, however, they often become clogged resulting in thereafter effecting a siphonic action as above referred to.

It is therefore an object of the present invention to provide a device for use in connection with water closet flush tanks inlet valves which will prevent a siphonic action under the conditions above stated.

Siphonic action also occurs under the conditions above stated with usual flush valves in fact a more undesirable condition as the siphonic action draws water in the toilet bowl through ports within the flush valve and bowl into the system.

Another object is to provide an attachment for use in connection with toilet flush valves which will positively prevent water in the toilet bowl from being drawn therefrom into the water system by siphonic action under the conditions above set forth.

Other objects and advantages will be apparent from the description reference being had to the accompanying drawing in which:

Fig. 1 is longitudinal section taken through a toilet flush tank.

Fig. 2 is a vertical section taken on line 2—2 of Fig. 1, showing the device of the invention connected to the usual ball cock valve.

Fig. 3 is an enlarged vertical section taken through the improved device.

Fig. 4 is a horizontal section taken on 4—4 of Fig. 3.

Fig. 5 is a side elevation of a toilet bowl (parts being broken away and shown in section) together with a flush valve equipped with the improved device.

Referring more specifically to the drawing, 10 designates a usual toilet tank in which is mounted

a vertically disposed inlet pipe 11 that is provided at its upper end with a valve housing 12. Formed on the valve housing and communicating with its interior is an elbow 13 from which extends downwardly a discharge pipe 14, which pipe serves to 5 silence the discharge of water into the tank 10.

Communicating with the interior of the valve housing and extending therefrom is a conduit 15, commonly referred as the refill tube which conveys water from the valve housing into the 10 overflow pipe 16 during flushing and refilling of the toilet bowl.

Slidably mounted in the valve housing and arranged to engage a seat 17, therein is a plunger valve 18 that serves to shut off water entering 15 the tank when the proper water level has been reached, movement of the valve being effected by a float 19 through the usual linkage 20 and arm or lever 21 connected thereto. While the above parts are of standard construction they 20 have been shown and described in order to more clearly bring out the operation of the present invention in connection therewith, the device being generally designated at 22.

Device 22 consists of a hollow body housing 23 having a reduced lower end portion 24 in which is mounted a member 25 that supports a ball valve 26. Ball valve 26 is hollow in order to render the same buoyant and serves to prevent discharge water into the tank 10 during filling of the same, 30 at which time the ball engages a seat 27 and closed a port 28 formed in a plug 29 that is screw threaded into the upper end of the body 24.

Member 25 is provided with a plurality of up-standing arms 30 which serve to guide the ball 35 valve towards the seat 27, and has a plurality of ports 32 formed therein at a point below the ball valve. The member 26 is externally threaded as indicated at 33 for connection with an elbow 34 which in turn is adapted to be connected to the valve housing as shown in Fig. 2.

Assuming that the conduit or refill tube 15 is clogged (under conditions when the flush tank is not equipped with the device 22) the tank partially filled, the water supply diminished or shut 45 off and a valve or faucet located at a lower level than the tank is opened, a siphonic action will take place drawing water upwardly through the pipe 14, thence through valve housing 12, and downwardly through pipe 11 into piping leading 50 to the faucet that has been opened.

Siphonic action, under conditions above referred to is prevented by the device 22, due to equalizing the atmospheric pressure within the valve housing and pipe 14 through the ports 32 55

and 28. Referring more specifically to Fig. 5, 32 designates a conventional toilet bowl having a flushing rim 33 and an auxiliary duct 34 formed therein that communicates with an inlet pipe 35 which in turn is connected to a usual flush valve 36.

The siphonic action breaker device 22 of the construction above described is adapted to be connected with the flush valve 36 at a point below the lower piston valve therein not shown.

Tilting of the oscillating lever 38 of the flush valve 36 releases the pressure in its upper chamber, the action of which permits opening of said valve due to the hydrostatic pressure in the supply pipe resulting flushing of the toilet bowl.

The flushing action decreases and finally stops when the pressure in the chamber in the flush valve again becomes equalized with the pressure in the supply pipes through the by-pass not shown forcing the diaphragm or plunger downward to a seated position.

During the flushing operation, a Venturi action is formed through the siphonage breaker 22, should this action cease through lack of velocity, the same action takes place in the siphonage breaker as heretofore described in connection with the ball cock valve.

In instances when water pressure in the supply pipe is low, (due either to excessive use or from a shut off) a vacuum will be created in the piping leading to the flush valve should a valve or faucet

at a lower level then be opened. At such times pressure in the flush valve chamber will be relieved through the by-pass tube or port (not shown) permitting the tilting or lifting of the plunger or diaphragm by atmospheric pressure exerted on the surface of the water in the toilet bowl causing the same to pass therefrom through the duct 34 into the supply pipe.

Under such conditions the supply pipe forms the long leg and the duct 34 and flushing rim 33 of the toilet bowl the short leg of the siphon should a valve or faucet at a lower level be opened. Siphonic action through a siphon thus established is prevented by equalization of air pressure on the water in the toilet bowl flush valve through the ports 28 and 32 in the device 22.

We claim:

A siphonage breaker for toilet flushing systems comprising a tubular body member having an enlarged upper chamber, a ball valve support 20 mounted in said body member and forming a seat, a hollow ball normally engaging said seat, a plug having a port and a seat formed therein mounted in and closing the upper end of said body member, there being a plurality of ports in 25 said valve support below the seat therein and a plurality of upstanding arms thereon for guiding said ball into engagement with the seat in said plug for the purpose set forth.

GEORGE L. SMITH. 30
